CALCULATING MACHINE

William Ball, Wallington, England, assignor, by direct and mesne assignments, to British Adding and Calculating Machine, Limited, London, England

Original application May 31, 1930, Serial No. 458,629, and in Great Britain August 14, 1929. Divided and this application August 13, 1931. Serial No. 556,834

11 Claims. (Cl. 235—60)

This invention relates to calculating machines and is a division from application Serial No. 458,629, filed 31st May, 1930, Patent No. 1,930,870 granted Oct. 17, 1933.

5 The chief object of this invention is to provide improved, simple and efficient mechanism for setting the mechanism of the machine in accordance with a predetermined item as represented by the keys or stops depressed.

10 A further object of this invention is to provide such setting mechanism which, when used in connection with a keyboard of a calculating machine, such as shown in the parent case will enable well spaced keys to be provided and which

15 conversely will also allow of the keys or stops to be set close together when necessary, while further, such setting mechanism which will enable a large number of keys or stops in the denominational column to be provided. A still further object of the invention is to provide such setting mechanism in which the number of parts is reduced to a minimum and in which the wear on the moving parts is considerably reduced thereby enabling the mechanism to give efficient and long service.

According to the invention, therefore, in a calculating machine comprising a plurality of denominational columns such as that shown in the parent case and including movable actuating 30 members for the totalizer wheels and separate setting members therefor adapted to co-operate with depressed keys in the associated denominational column, each setting member is arranged to move differentially with respect to the associated actuating member and means is provided for causing the differential movement to produce a rotational movement of said setting member towards the keys to the associated denominational column so that the setting member co-40 operates with a depressed key in the column to effect a setting of the totalizer wheel corresponding to the key designation.

By such an arrangement adequate clearance for a large number of keys in the associated denominational column is provided and the travel of and wear on the setting member is considerably reduced.

The invention will be more clearly understood with reference to the following description and 50 to the accompanying drawings which show the features of the invention as applied to the preferred form of calculating machine shown in the parent case, only those figures being shown which are deemed necessary for a complete understanding 55 of the invention. It will be understood, how-

ever, that the features of the invention although illustrated with reference to the preferred form of the machine can be applied to other forms by suitable modification thereof and the invention must, therefore, not be considered limited to the calculating machine shown in the drawings hereinafter referred to.

In the drawings,

Fig. 1 is a sectional plan of the machine;

Fig. 2 is a view from the left of a calculating unit detached, the column showing nine numeral keys in addition to the column release key at the extreme right hand end and corresponding to one of the pounds columns in the machine;

Fig. 3 is a corresponding view from the right of the calculating unit shown in Fig. 2 with type bar omitted and the totalizer wheel disengaged from the actuating rack to clearly indicate the normal position thereof when the unit is mounted in the machine; and

Fig. 4 is an end view of calculating unit shown in Figs. 2 and 3;

Fig. 5 is a detail sectional perspective view of the front end of the unit only with the column release key omitted and showing more particularly the construction of the stubs of the numeral keys and the staggering of the abutments on the setting rack.

Fig. 6 is an enlarged right hand end view of Fig. 2 showing only the column release key in depressed condition, and the associated clearing bar which co-operates with all the keys in the section;

Fig. 7 is a similar view to Fig. 6 with the column release key in a non-depressed or released condition;

Fig. 8 is a detail perspective view of the clearing bar. The reference numerals used herein correspond with those employed for similar parts in the parent case.

Although the machine is readily adaptable to power operation, the preferred form illustrated has been shown as hand operated.

Referring to the drawings the main operating shaft is identified by the numeral 1 and is carried in bushings on each of the main side frames 3, an operating handle 4 keyed to the shaft 1 projecting at the right, as customary.

The side frames 3 are identical, and each is provided with a pair of open housings arranged to receive hardened steel bolts 10 and 11 running the width of the machine, and serving to carry an assembly of calculating units 12, one of which is shown in Figs. 2 and 3.

The construction of the side frames 3 and of

the sectionalized form of the keyboard is clearly shown in the parent case a series of spacing washers 15 of dimensions corresponding to the width of each section 16 of the keyboard associated with each unit 12 are arranged along the bolts 10 and 11 to fixedly locate the several units.

Referring now more particularly to Figures 2 and 3, where the detachable unit 12 is illustrated, 16 is a keyboard section as before mentioned, being secured by bolts or rivets to the out-turned flanges 26 and 27 of a plate 28, hereinafter termed a stretcher plate, forming the foundation of the unit 12.

This stretcher plate 28, as clearly shown in Figures 2 and 3, is a plain stamping of sheet metal, blanked and pierced to carry the various parts of the calculating mechanism, and flanged at 30 to carry a guide plate 31, through which the stubs of the keys of the section project.

20 The guide plate 31 is also tied to the top plate 16 by pillars 33, 34 and 35, whereby substantial rigidity of the unit is attained, and the numeral keys 32 and the column release keys 32a both have flat shanks 36 passing through aligned laterally extending slots 37 and 38 in the top plate and guide respectively.

30 The totalizer wheel 20 of the unit is carried on a spindle 89a mounted on a bell crank 90 pivoted to the stretcher plate 28 at 91, the setting of the wheel 20 being effected by means of differentially geared actuating and setting mechanism including a separate setting rack 58, which by reason of the differential movement between the elements of said mechanism, is moved to co-operate 35 with a depressed key 32 in the column and thereby set the wheel 20 in accordance with the key designation as will be hereinafter described.

40 The column release key 32a is normally depressed and locks the setting rack 58 in the initial position as shown in Fig. 2. The means for releasing the setting rack when a numeral key is depressed will now be described. Each key shank 36 of the keys 32 and 32a of each column or section 16 is provided with an outstanding lug 45 45 on the flat face of the shank, with which lug a compression spring 40, fixed to the guide plate 31, is connected so that the key is pushed upwardly by the spring 40 to be adjacent the under-side of the top plate 16.

50 On both the side edges of each key shank 36 two projections 42, 42a are formed, one for limiting the upward movement and the other for limiting the downward movement of the key, while a cam surface 41 and a recess 41a are also provided for co-operating with a clearing bar 45 extending the length of the keyboard section 16.

60 The clearing bar 45 is substantially of L-shape section, see Fig. 8, and is pivotally mounted on the stretcher plate 28 by means of cylindrical extension end pieces 46, 47, mounted in bearings formed in inturned flanges 48 and 49, provided one at each end of the stretcher plate 28 and adjacent the top plate of the keyboard section 16.

65 As shown in Fig. 7, when a key is not depressed the short arm 45a of the clearing bar 45 bears against the lower portion of the cam surface 41 on the key shank 36 by means of a tension spring 50, fixed to the guide plate 31 and connected to the short arm 45a substantially centrally of the clearing bar 45, see Fig. 2, but on depression of the key, see Fig. 6, the cam surface 41 causes the clearing bar to rock to the right about its pivotal axis until the recess 41a is reached, when 70 the short arm 45a snaps into the recess to retain

the key in the depressed condition against the compression in its spring 40.

Thus, with the numeral keys 32 in undepressed condition and the associated column release key 32a depressed as shown in Fig. 2, and locking the setting rack 58, the short arm 45a engages with the cam surfaces 41 on the numeral keys and with the recess 41a in the column release key, but upon depression of a numeral key the consequent rocking of the clearing bar disengages the short arm 45a from the recess 41a in the column release key so that the latter restores by means of its spring 40, and releases the setting rack 58.

80 The column release keys 32a are returned to their locking position (that is depressed and engaging the first abutment on the setting rack 58) by means of pins 171 mounted on a rocking shaft 170, each pin 171 engaging in the slot 172 of the associated column release key, so that when the shaft 170 is rocked to rotate the pins 171 downwardly, the latter pull the non-depressed column release keys into the depressed position. This 85 operation occurs after the setting racks have been restored to the normal position, as shown.

90 With reference now more particularly to Figs. 2 and 3, the stretcher plate 28 is provided with a number of slots 51, 52, 54, 44a and 44b, which form guides for mounting both the differentially geared actuating and setting rack mechanism hereinbefore referred to, this mechanism being 95 such that the actuating rack is adapted to move differentially with respect to the associated setting element.

99 The differentially geared mechanism includes a linearly movable pinion for operating the racks 110 and is similar to that described in my United States Patent No. 1,742,053 and again employed in the arrangement described in my United States patent application (Serial No. 243,660), and comprises an upper normally movable rack 115 53 provided with headed pins 69 riding in the slots 51, 52, a normally stationary lower rack 57, hereinafter referred to as a transfer rack, provided with headed pins 44 riding in the slots 44a and 44b, and an actuating rack 56 formed with 120 a slot 66 engaging with a headed pin 67 mounted on the stretcher plate 28. The transfer rack 57 is normally held in the stationary position by a pin 101 on a transfer lever 94 engaging in a notch 103 in the rack 57, and is only released for 125 transfer under such conditions as are described in the parent case.

130 The linearly movable pinion designated 55 is mounted on the stretcher plate 28 by means of a pin 55a riding in the slot 54, a washer 55b maintaining the pinion in position on the plate 28 and the pinion engaging with both the upper and lower racks 53 and 57 respectively and being connected to and mounted on the actuating rack 56 by the pin 55a.

135 With this arrangement it will be seen that the movement of the upper rack 53 is in all cases double that of the pinion 55 when the transfer rack 57 is stationary, and consequently double the movement of the actuating rack 56.

140 With reference now to the setting rack 58 herefore mentioned, in contradistinction to either of the constructions disclosed in the prior specifications heretofore referred to, in the present arrangement a separate and rising setting rack 145 58 is employed, the forward end of which is pivoted at 59 to the upper rack 53, while the other end is provided with a stub 60 arranged to ride in an inclined guide slot 61 formed in the body 62 of the actuating rack 56, the arrange- 150

ment being such that during the movement of the differentially geared mechanism from the zero position illustrated, the setting rack rises towards the keyboard by means of the guide slot 61 and the differential movement between the actuating rack 56 and the upper rack 53, it being understood that since the upper rack 53, and therefore the setting rack 58, gains on the actuating rack 56, the stub 60 and the rear end of the setting rack 58 will be caused to ride up the inclined slot 61 in the actuating rack 56, to bring the setting rack into co-operation with a key which may have been depressed in the associated column.

15 In the prior specifications heretofore referred to, a single stop or abutment was mounted on the upper moving rack for cooperating with any depressed key in the column, which resulted in the travel of the upper rack being unduly large, and 20 in considerable impact arising between the abutment and a depressed key, especially if such key was of a high numerical value, but according to this arrangement the provision of a separate setting member rising towards a depressed key 25 considerably reduces the impact against the key and enables the travel of the upper rack 53, and consequently of the setting rack 58, to be reduced, and, further, it is possible to use a separate abutment for each key of the column, 30 whereby the wear on any individual abutment is considerably reduced, and the durability and freedom from adjustment of this part of the differentially geared actuating and setting mechanism ensured by the reduction of the impact 35 between the setting rack abutment 63 and the keys.

The abutments 63 are arranged so that the forward or right hand abutment 63, seen in Figure 2, co-operates with the 0 or column release key 32a, the second abutment with the 1 key, and so on, the last or left hand abutment co-operating with the 8 key, and the end of the slot 61 in the actuating rack 56 being employed as the final or 9 abutment corresponding with the 45 full travel of the setting rack 58, and thereby eliminating the necessity for a further abutment on such setting rack, although, if desired, of course, such an abutment could be provided to co-operate with the stub of the 9 key.

50 It will be understood that for a pence column twelve keys will be provided, and correspondingly eleven or twelve abutments 63, according to whether the end of the slot 61 is employed as a limit or not, and that the number of keys and 55 co-operating abutments is adapted to the requirements of each particular case, the particular unit illustrated being one of the pounds columns of the pounds, shillings and pence machine illustrated as the preferred embodiment.

60 The elements of differentially geared actuating and setting mechanism are shown in the normal or zero position, the 0 or column release key 32a at the right of the column being depressed and engaging its abutment to maintain the setting 65 rack 58 and the remainder of the mechanism therein.

Movement of the differentially geared actuating and setting mechanism after a key 32 has been depressed, is controlled from the main operating shaft 1 of the machine through an operating member constituted by a rocker 70 pivoted to a shouldered pin 71 at the foot of the stretcher plate 28, and having three arms, the first 72 being provided with an anti-friction roller 73 which 75 when the unit is assembled in the machine abuts

against a control arm 74 on the main operating shaft 1, the roller, if permitted tending to follow the arm 74 under spring action as hereafter explained during the initial stroke of the handle 4, which, as customary, is in the direction of the arrow A in Fig. 2.

80 A second arm 75 forms the operative connection with the pinion 55 of the differentially geared actuating and setting mechanism, being formed with a slotted end 76 in which rides a pin 77 carried by a link 78 in turn carried on the pivot 55a of the pinion 55.

85 A pin 79 on the arm 75 and a second pin 80 on the link 78 are connected by a coil spring 81 which, during operation of the machine, maintains the pin 77 to the right of the slotted end 76 as shown, and ensures that the setting rack 58 is maintained in the normal position during the depression of the column release keys towards the end of the ultimate return stroke of the main shaft, as is explained in the parent case Serial No. 458,629. It will be noted that the position of the rocker 70 and of the pin in the slotted end 76 thereof as shown in the drawings is that when the handle 4 has been moved slightly forward 90 without a key being depressed. Thus, if the handle is restored the slotted end would move across the pin 77 until the latter abuts against the opposite end to that shown.

95 A third arm 82 completes the rocker 70, and is provided with an anti-friction roller 83 which cooperates with an oscillating lever 84 pivoted to the stretcher plate 28 at 85 to which a settable type bar 240 is connected, the said type bar forming part of the printing mechanism fully described and claimed in divisional application Serial No. 556,838.

100 To enable the roller 73 to follow the arm 74 and the differentially geared actuating and setting mechanism to be substantially self-acting, a spring 64 is connected between the end of the setting rack 58 and a pin 65 on the actuating rack 56 so as to be under tension, in the normal position of the said mechanism, whereby when 105 the setting rack 58 is unlocked, by releasing the column release key 32a, and the handle 4 is moved forward, the setting rack 58, the actuating rack 56 and the pinion 55, together with the rocker 70 automatically move rearwardly due to the tension in the spring 64, the roller 73 thus following the arm 74, and the rate of the movement of the parts being governed by the movement of the handle. It will be noted that the connection between the arm 74 and the arm 72 is 110 a detachable and disconnectable one permitting this automatic movement until the setting rack 58 is arrested by an abutment 63 engaging with a depressed key, whereupon the whole of the actuating mechanism will be brought to rest and the arm 74 will leave the roller 73 as the stroke 115 of the main shaft is completed. During the return stroke of the handle 4, the arm 74 abuts 120 against the roller 73 to move the rocker 70 forwardly and thereby restores the mechanism 125 against the tension of the spring 64. To facilitate the automatic movement of the parts, a further tension spring 64a is provided connected between 130 points on the stretcher plate 28 and the rocker 70, or the spring 64a, may be used in place of the spring 64.

135 Assuming that, in place of the column release key 32a shown depressed in Figure 2, the 8 numeral key is depressed and the operating handle 4 turned in the direction of the arrow A, the setting rack 58 and the actuating rack 56 will move 140

145

150

to the left (Figure 2) the rocker 70 turning in an anti-clockwise direction as the arm 74 rotates away from the roller 73 until the respective abutment 63, i. e. the left hand one, engages the stub of the 8 key, when the further movement of the actuating rack 56 will be arrested and the arm 74 will leave the roller 73.

In this position the actuating rack 56 will have moved a spaced equivalent to eight facets of the 10 totalizer wheel 20, and if the wheel 20 through its pinion 68 be then engaged with the actuating rack 56 and the operating shaft 1 returned to its initial position, the totalizer wheel would show a reading corresponding with the item set up in 15 the key column, i. e. the number 8.

The engagement operations of the totalizer wheels 20 are fully described in the parent case.

As appears more clearly from Figure 3 the slots 20 51 and 52 are arranged of greater length than the travel of the rack 53, and their extremities are provided with apertures 51a and 52a respectively, through which the heads of the pins 69 which carry the rack 53 can pass and the rack thereby be removed or fitted, suitable spacing washers 25 being provided, preferably integral with the pins, of standard thickness throughout the machine, to reduce the friction where desirable.

Similarly, the heads of the pins 44, carrying the lower or transfer rack 57 and riding in the 30 slots 44a and 44b, can pass through similar apertures in the stretcher plate 28, so that the transfer rack may be removed, and in this manner assembly of the unit 12 or replacing of any 35 parts is greatly simplified.

With reference more particularly to Figure 5 it will be seen that the abutments 63 on the setting rack 58 are alternately staggered as at 63a and the stubs of the key shanks 36 of the numeral keys 32 are each formed with a lug 43, the lugs 40 in successive keys being staggered to allow, as the setting rack 58 rises towards a depressed key, the abutment corresponding to the next higher numeral key to pass the lug 43 of the depressed key. Thus a larger abutment may be employed 45 to give a more positive co-operation with the keys, at the same time allowing abutments of higher numeral keys to pass a depressed lower numeral key without interference. It will be understood that provision of staggered lugs in the key shanks 50 is equivalent to staggering the actual key shanks and allows of a standard key of uniform dimensions to be used.

As an alternative to staggering the abutments on the setting rack, two or more of such racks 55 may be provided the one having the abutments 63 and the other the abutments 63a.

By the provision of such a setting rack or racks increased clearance of the key stems is obtained and the durability and freedom from adjustment 60 of this part of the machine improved by giving a clearance adequate to allow for any wear in the parts.

From the foregoing, it will be seen that by arranging the setting rack 58 separate from the 65 actuating rack 56 adaptation to various requirements is also provided for, while with the rising setting racks employed in the preferred embodiment any shock imparted to the key shanks is reduced and the load more evenly distributed throughout the stroke of the actuating mechanism, the plurality of abutments provided also reducing wear to a minimum.

It will be understood that in cases where there are only a small number of keys to a column, for example, in the farthings column of the ma-

chine shown, or where only one or two keys are necessarily operative as in the tens of shillings columns of a pounds, shillings and pence machine, a simpler form of setting rack can, of course, be used, such as one with a single abutment.

Although the invention has been more particularly described in connection with its use as a setting mechanism for a calculating machine comprising detachable interchangeable denominational units, it will be understood that the invention can be applied with advantage to other forms of calculating machines employing actuating racks which have differential movement with respect to the setting racks.

Many modifications of the above described constructional features will be apparent to those skilled in the art to which this invention relates. For example, instead of employing a straight inclined slot, as above described, a curved slot may be employed to assist the rising action of the setting member.

Among the many advantages accruing from the adoption of this invention may be mentioned the following:—ready conversion to varying denomination requirements, a standard key may be employed for all units in any column, whereby manufacturing and production costs are materially reduced; the wear on the moving parts is reduced whereby there is less likelihood of the machine getting out of order; and, further, the whole of the mechanism may be cheaply produced without any elaborate tools and may be easily and quickly assembled by means of unskilled labour.

What I claim is:

1. A calculating machine comprising a plurality of denominational columns each having associated therewith, a totalizer wheel, an actuating member for the totalizer wheel, a setting member adapted to co-operate with depressed keys in the column, means for moving the setting member differentially with respect to said actuating member, and means for causing the differential movement to produce rotational movement of said setting member towards the keys of said column to co-operate with a depressed key therein for effecting a setting of the totalizer wheel corresponding to the key designation whereby adequate clearance for a large number of keys is provided and the travel of and wear on the setting member is reduced.

2. A calculating machine comprising a plurality of denominational columns each having associated therewith a totalizer wheel and differentially geared actuating and setting mechanism for the totalizer wheel including a separate setting member pivotally mounted on a member of said mechanism differentially movable with respect to the actuating member of said mechanism, means for actuating said mechanism to produce the differential movement between the members thereof, abutments on said setting member for co-operating with depressed keys in the column, and means whereby the differential movement between the members of said mechanism imparts both longitudinal and rotary movement to the setting member to bring an abutment against a depressed key for effecting a setting of the totalizer wheel corresponding to the key designation.

3. A calculating machine comprising a plurality of denominational columns each having associated therewith a totalizer wheel and differentially geared actuating and setting mechanism for the totalizer wheel including a separate setting member pivotally mounted on a member of

action to cause thereby differential movement between said actuating rack and said movable rack, means for detachably and disconnectably connecting said operating member with the main shaft to permit of the automatic movement of the operating member with the main shaft until arrested by an abutment on the setting member engaging a depressed key, and a guide on the actuating rack for the setting member at its free end, whereby said differential movement causes the setting member both to move linearly with said movable rack and to rotate towards the keys to bring an abutment against a depressed key for effecting a setting of the totalizer wheel corresponding to the key designation.

10. A calculating machine including a main operating shaft and comprising a plurality of denominational columns each having associated therewith a totalizer wheel, and actuating rack for the totalizer wheel, a linearly movable rack, a stationary rack, a movable pinion engaging with both said movable and stationary racks and carrying said actuating rack, a separate setting member pivotally mounted on said movable rack, abutments on said setting member for co-operating with depressed keys in the column, means normally locking the setting member, means whereby the setting member is released when a key in the column is depressed, an operating member for said pinion formed for detachable and disconnectable connection with the main operating shaft, an operative connection between said operating member and said pinion, a spring connected between the actuating rack and the setting member whereby on release of the setting member said pinion moves automatically under the spring action to cause thereby differential movement between said actuating rack and said movable rack, means for detachably and disconnectably connecting said operating member with the main shaft to permit of the automatic

movement of the operating member with the main shaft until arrested by an abutment on the setting member engaging a depressed key, a lateral projection on the free end of the setting member riding in an inclined guide slot in the actuating rack whereby said differential movement causes the setting member both to move linearly with said movable rack and to rotate towards the keys to bring an abutment against a depressed key for effecting a setting of the totalizer wheel corresponding to the key designation.

11. A calculating machine comprising a plurality of denominational columns wherein the numeral keys of each column are provided with lugs, the lugs of successive keys being staggered and each column has associated therewith a totalizer wheel, an actuating rack for the totalizer wheel, a linearly movable rack, a stationary rack, a movable pinion engaging with both said movable and stationary racks and carrying said actuating rack, means for moving said pinion to cause thereby differential movement between said actuating rack and said movable rack, a separate setting member pivotally mounted on said movable rack, abutments on said setting member for co-operating with depressed keys in the column and arranged in staggered relation corresponding to the stagger of the lugs on said keys whereby abutments corresponding to higher numeral keys can pass a depressed lower numeral key without interference, and a guide on the actuating rack for said setting member at its free end whereby said differential movement causes the setting member both to move linearly with said movable rack and to rotate towards the keys to bring an abutment against a depressed key for effecting a setting of the totalizer wheel corresponding to the key designation.
